UNITED STATES PATENT OFFICE.

WILLIAM A. MILES, OF COPAKE IRON WORKS, NEW YORK.

CONDENSER FOR STEAM-PUMPS.

SPECIFICATION forming part of Letters Patent No. 271,097, dated January 23, 1883.

Application filed December 21, 1882. (No model.)

To all whom it may concern:

Be it known that I, WILLIAM A. MILES, of Copake Iron Works, in the county of Columbia and State of New York, have invented an improvement in Condensers for Steam-Pumps, of which the following is a specification.

In another application I have set forth the main features of my improvement to relate to a valve that closes when the steam-pressure is less than the pressure in the suction water-way, so as to prevent water flowing into the steam-pipe. The present invention is in the same class of appliances, and relates to the following features: I combine with the suction water-way and the exhaust-steam pipe opening into the same an expansion-chamber which receives the exhaust-steam and allows the same to flow more gradually into the suction-pipe than it would when the exhaust-steam passes direct to the water-way. I also construct the valve at the end of the exhaust-steam pipe in a peculiar manner, and I employ a device for removing any air that may accumulate in the suction water-way, thereby preventing the pumping operation being interfered with, especially in cases where the pump is running very slow and the flow of water is not sufficient to carry with it any air that may come in with the exhaust-steam.

In the drawings, Figure 1 is a vertical section of the apparatus. Fig. 2 is a view of a modification in the exhaust-steam valve. Fig. 3 is a section in larger size of the valves and parts at the top and bottom of the air-chamber.

The pipe *a* is to extend to any suitable pumping apparatus, and the pipe *b* is the suction or rising pipe that leads from the water, either direct or with siphon-legs of greater or less length between the pipes *a* and *b*. The objects of having siphon-legs having been set forth in my aforesaid application, I remark that they are beneficial when used under similar conditions with the parts herein named; but some of the present devices are not necessarily applied with said siphon-legs.

I prefer to use a branch pipe, *a'*, with a cock or valve, *a²*, in it, so that in starting the pump this valve may be opened, and after the water has been drawn to the pump this valve may be closed gradually and the water drawn up to fill the siphon.

The exhaust-steam from the pumping-engines passes by the pipe *e* into an expansion-chamber, *f*, of suitable size and shape, preferably of about the same contents as the steam-cylinder, so that there will be ample room for the puff or sudden expansion of the exhaust-steam, and the pipe *h* leads the steam into the suction water-pipe *b*, near the upper part thereof. The expansion-chamber allows the steam to pass nearly continuously into the suction water-pipe instead of entering the same suddenly or with a puff. There is to be a check-valve to prevent any water from passing back into the steam-pipe or expansion-chamber. This check-valve may be in the pipe *h*, as seen at *l*, Fig. 2; but I prefer to use the valve shown in Fig. 1, in which the pipe *h* passes vertically into the suction water-pipe, and to the end of it is screwed a socket, *o*, having legs on its lower end connecting to the socket the cup *p*, and the valve *l* is in the form of a ring surrounding and guided by the socket *o*, and of a size to rest at its outer edge upon the edges of the cup *p*, and thereby close when the vacuum in the exhaust-steam pipe *h* is greater than that in the suction water-way; but when the said vacuum is greatest in the suction water-way the steam escapes freely into the water and is condensed, thus maintaining in the exhaust to the engine a vacuum as great as that in the suction water-way. In all instances the steam issues in a thin sheet or stratum from the pipe *h* into the suction-pipe. In Fig. 1 this stratum of steam issues between the edge of the cup *p* and the edge of the valve *l*. In Fig. 2, where the check-valve *l* is in the pipe *h*, the stratum of steam issues between the edges of the flaring mouth at the end of the pipe *h* and the edge of a deflector, *l'*, that is supported by said pipe *h*.

Sometimes water of condensation will form in the expansion-vessel *f*, and to remove the same I employ a pipe, *n*, leading from the bottom of said vessel, and terminating within the water-way in a nozzle opening in the direction of the flow of the water, so that any water of condensation will be sucked out of the said expansion-vessel, and I employ a check-valve at *m* in this pipe *n*, to prevent water passing back into the expansion-vessel.

When the pumping-engine is running very slow, the air that may pass with the steam into

the suction water-pipe may accumulate in the top bend of the suction-pipe. To remove the same I adopt an automatic discharge, constructed as follows:

5 The cylinder or vessel *r* is above the top of the suction-pipe, and I arrange two valves, *s* and *t*, connected by a stem, *u*, so that when the vessel becomes filled with air a steam valve or plug, 3, is operated by the float *v*, and steam is admitted to move the valves *s* and *t* and allow water to run in and drive the air out, after which the valve or cock 3 is moved the other way by the float and the steam shut off, and the parts fall by gravity 10 and resume their normal position. In carrying out this feature I make the valves *s* *t* cylindrical and place them in the cylinders 5 and 6, and around each valve there are two channels cut or turned. There is a water-way, 7, to the cylinder 5 and an air-tube, 8, opening at the lower end into the suction water-way *b* at the highest point, and there is a tube, *t'*, extending from 5 up to near the top of the air-vessel *r*.
15 The float *v* is free to move up and down on the stem *u*, and at its extreme downward movement it rests upon the cross-arm 10 and moves the same downwardly and with it the rod 12, that passes through a small gland in the top 20 of the air-vessel and connects with the arm 13 of the three-way cock. From this three-way cock there is a port, 14, leading to the lower end of the cylinder 6, below the piston-valve *t*, and the steam-pipe 24 leads also to this three-way cock, and 15 is an escape at this cock to the atmosphere.
25 At the cylinder 6 there is an air-passage at 18 and the water-pipe 19. The parts are so constructed that in the normal position the valve 30 *t* closes the ports of the air-passage 18 and the water-pipe 19, and the valve *s* opens the water-pipe 7 and the passage 8 through the air-pipe *t'*. Hence, presuming that the vessel *r* is full, or nearly so, of water, the bubbles of air pass 35 up freely from the suction water-pipe, through the pipe 8 *t'*, into the vessel *r*, and at the same time the water runs out therefrom into the suction water-way by the pipe 7. When, now, the water has run out of *r* and its place been occupied with air, the float *v* has descended, and by its weight it has moved the arm 10 and rod 40 12 and turned the three-way cock 3 sufficiently to admit steam below the cylindrical valve *t*, which instantly lifts the same, and also the cylindrical valve *s*. This movement closes the air and water ports 7 and 8, and by the cylinder *t* opens the water-port 19 and the escape air-port 18. Consequently water runs into this vessel *r* by the pipe 19 and passage 20, driving 45 out the air by the said port 18. When therefore the air has been expelled, and the float, rising, moves the arm 21, rod 12, and three- 50

way cock 3, the steam is shut off, an escape opened for the same, and the cylindrical valves *s* and *t*, dropping, restore the parts to their normal position, ready for the air from the suction water-way to pass into the chamber and gradually displace the water, as before mentioned.
55

I remark that the valves may be moved periodically by hand, or by a connection to a steam-engine or other suitable means, so as to dispense with the float.
60

I do not limit myself to any particular character of valves, as they may be varied so long as the air and water are received and discharged alternately to free the suction water-way of any air passing into the same.
65

I claim as my invention—

1. In a condensing apparatus for steam-pumps, the combination, with the suction water-way and the exhaust-steam pipe opening into such water-way, of an expansion-vessel receiving the steam before it reaches the water-way, substantially as and for the purposes set forth.
70

2. The combination, in a condensing apparatus for steam-pumps, of a suction water-way, an exhaust-steam pipe opening into such water-way, an expansion-vessel, and a check-valve, substantially as set forth.
75

3. The combination, with the suction water-way and the exhaust-steam pipe, of a cup at the end of such steam-pipe and an annular valve surrounding the steam-pipe and resting at its edges upon the cup, substantially as set forth.
80

4. In a condensing apparatus for steam-pumps, the combination, with the suction water-way and the exhaust-steam pipe entering such water-way, of an air-vessel above the suction water-way and an opening leading into such air-vessel, for the purposes and substantially as set forth.
85

5. The combination, with the suction water-way in a pumping apparatus, of an air-vessel above the highest point of such water-way, an opening and valve for air to pass from the water-way into the vessel, an opening and valve for water to pass out of the air-vessel into the water-way, and means for supplying water into the air-vessel for displacing the atmosphere, substantially as set forth.
90

6. The combination, with the air-vessel, of the sliding valves *s* and *t* and their respective pipes and ports, the float, and the three-way cock or valve to admit steam to raise the valves *s* and *t*, substantially as set forth.
95

Signed by me this 16th day of December, A. D. 1882.

WILLIAM A. MILES.
